UNITED STATES PATENT OFFICE.

ALFRED SMITH AND SIMEON JACKSON, OF KEIGHLEY, ENGLAND.

MEANS FOR AUTOMATICALLY CHANGING SHUTTLES IN LOOMS.

SPECIFICATION forming part of Letters Patent No. 713,702, dated November 18, 1902.

Application filed May 10, 1901. Serial No. 59,563. (No model.)

To all whom it may concern:

Be it known that we, ALFRED SMITH and SIMEON JACKSON, subjects of the King of Great Britain, residing at Keighley, in the county of York, England, have invented certain new and useful Improvements in Means for Automatically Changing Shuttles in Looms on Failure of Weft, of which the following is a specification.

This invention relates to the class of loom in which when the weft fails or breaks the shuttle is automatically replaced by one from a magazine. This magazine is suitably placed at the front of the loom and is prepared to receive a number of shuttles containing cops or bobbins to be used in weaving.

Our invention consists of the application of an automatic motion which works in combination with all the movements comprised in the replacement of the shuttle; also, in connection with the weft-fork and the driving motion.

In the drawings, Figure 1 is an end view of a portion of a loom, showing the magazine. Fig. 2 is a front view of the same. Fig. 3 is an end view of a portion of the loom looking in the reverse direction from that shown in Fig. 1. Fig. 4 is a front view of the parts shown in Fig. 3. Figs. 5 and 6 are plan views of the parts shown in Fig. 4, showing said parts when the loom is at rest and in operation, respectively. Fig. 7 is a plan view of the parts shown in Figs. 1 and 2. Fig. 8 is a sectional view of the clutch mechanism. Fig. 9 is a detail side view of the tappets. Fig. 10 is a side view of the clutch mechanism. Figs. 11 and 12 are end views showing the mechanism for reversing the dobby-cylinder.

In this our invention the sides *a b*, rail *c*, shafts *d e*, and stand *f* may be of any ordinary construction. The magazine *g*, (see Fig. 7,) receiving the full shuttles *h*, is arranged as follows: One part, consisting of the four sides *i*, is rigidly connected by bracket *j* to the rail *c* of the loom. The other part, forming the bottom *k* of the magazine, is attached to the swing-arm *l*. In the projections *m n o p* we mount loosely two parallel rods *q r*. To the rod *r* are connected the fingers *s t*, and to the rod *q* are connected two rods *u v*, and to these latter is connected the plate *w*. The two rods *u* and *v* receive two screws *x y*, which

are in contact with the bottom *k* when the latter is at its normal or back position. Also a spring *z* (see Fig. 1) is attached to the rod *q*, 55 and the fingers *s* and *t* being connected by rod *l* work in unison with the rods *u* and *v*. Thus when the loom is in operation the shuttles are as shown in Fig. 1—that is, one is resting at the bottom of the magazine and the 60 others are supported by the fingers *s* and *t*. When a change of shuttle is being made and the bottom *k* moves forward, as hereinafter explained, the fingers *s* and *t* and rods *u* and *v* take up the positions shown in dotted center lines *8 9*, and the shuttles *h* are free to drop on plate *w*, which then acts as the bottom for the magazine, and as the bottom *k* moves backward to take up its normal position it comes in contact with the screws *x y*, 70 and thus the fingers *s* and *t*, rods *u* and *v*, plate *w*, and shuttles *h* again take up the positions shown in Fig. 1.

The swing-arm *l* fulcrums on the stud 2 and receives its motion by means of bowl 10, 75 lever 3, rod 4, lever 5, and spring 6 from the tappet 7. The swing-arm *l* when operated traverses to and from the slay-board, and if its full traverse be not required the spring 6 yields, and thus prevents breakage. 80

The swell or sweller is formed of two parts 11 and 12. The part 11 fulcrums on the stud 13 and forms the back of the sweller, and the part 12 fulcrums on the pin 14 and forms the front of the sweller. A pin 15 is attached to 85 the part 12 and projects through the part 11, and a spring 16 is applied to this pin 15. When a change of shuttle takes place, the pin 15, and with it the part 12 of the sweller, is pushed forward by the tappet 17, which 90 works in connection with same by means of the bowl 18, lever 19, rod 20, and lever 21, and thus the spent shuttle is ejected from the slay-board. When the loom is in operation, the parts 11 and 12 work together as an 95 ordinary sweller.

The box-front 22 is connected by studs 23 and 24 to a cross-head 26, and the studs 23 and 24 pass through sockets 33 and 28, which form part of the box-bottom 29. The cross-head 26 is operated vertically by the tappet 27 being brought into connection with same by the bowl 30, lever 31, and rod 32. The normal position of the box-front—that is, when

the loom is in operation—is shown by Fig. 1. When the change-motion is in operation, the box-front 22 is raised by the tappet 27 in order that the spent shuttle may be ejected and 5 replaced by one from the magazine.

The handle 34 has two positions, as is well understood. Fig. 6 represents its position when the loom is in operation, and Figs. 4 and 5 show its position when the loom is at 10 rest. The position of the driving-belt is determined by the handle 34, being connected with same by rod 42 and any other suitable mechanism. (Not shown.) When in contact with the fast pulley 35, it imparts motion to 15 the loom, and when in contact with the loose pulley 36 the loom is at rest and the change-motion may be operated from same, as hereinafter explained. The construction of the handle 34 is well understood—that is, as 20 regards the manner of retaining same in its operative position—also its spring, which tends to force it into its non-operative position. The handle 34 is brought into contact with the tappet 38 by means of the bowl 39 and 25 levers 40 41, these two levers being rigidly mounted on shaft 49. The lever 41, being connected by rod 44, raises the lever 45, and this latter by its projecting stud 46 pushes back the handle 34 into its operative position. Thus if by reason of the weft having 30 failed the handle 34 is released the belt is thrown onto the loose pulley 36, the loom is thus brought to rest, and the automatic motion is put into operation, when the tappet 35 38 as already described changes the position of the handle 34 and the loom is again put into operation.

The lever 45 has a projection 47, and an ordinary weight or spring for the brake of the 40 loom (not shown) is attached at the point 48. The handle 34 holds the lever 45 in its raised position by the said projection 47, and when released the lever 45 is also free to drop.

Our arrangement for connecting the weft-fork 50 to the automatic motion is as follows: 45 It is secured to the lever 51 in the ordinary manner, and on the latter we mount a movable plate 52, having a stud 53, to which is secured the spring 54. This plate 52 has two 50 slots 55 and 56, through which pass the two studs 57 and 58. In this manner the plate is free to slide on the said studs 57 and 58 and is also held in position. When the loom is in operation, the nose 59 is, as shown in Fig. 55 6, in contact with the finger 60, and when the loom is in its non-operative position and the change motion, as hereinafter explained, is in operation it is clear of same, as shown in Fig. 5. Thus when the weft has failed and 60 the lever 51 (and with it the nose 59 of plate 52) is being pushed by the well-known lever and eccentric arrangement to its back position, as shown by the dotted lines in Fig. 6, the nose 59 pushes back the finger 60. The 65 lever 51 and handle 34 are in contact. Thus when the lever 51 reaches its back position the handle 34 is released from its point of re-

tention and moves from the position shown in Fig. 6 to the position in Fig. 5, and, as already explained, the lever 45 is free to drop and the projection 47 of the latter comes in contact with the stud 53, thus carrying the nose 59 clear of the finger 60, which then again takes up its forward position. When the loom is restarted, the lever 45 is raised, 70 as before explained, and the projection 47 is clear of the stud 53 when by aid of the spring 54 it takes up the position shown in Fig. 6.

Our arrangement of the change-motion mechanism is as follows: We mount a pinion-wheel 61 (see Figs. 2 and 1) on the crank-shaft *d* of the loom, this pinion-wheel forming part of and revolving with the loose pulley 36. This pinion-wheel 61 transmits the motion by means of the intermediate wheel 62 85 to the wheel 63, and this latter has a concentric ring supplied with radial indents 65 and rotates loosely on the boss 66. The boss 66 is mounted loosely on the low shaft *e* and has a plate 67 attached to same, this plate being 90 adapted to receive the spring 68 and stud 69. On the boss 66 is fitted loosely the piece 70, having a slot 71 and nose 72, this piece 70 being movable on the boss 66 and being connected by stud 73 to the lever 74. The lever 74 is mounted loosely on the stud 69, and the spring 68 is applied to same. It also receives the stud 75. The stud 75 works in unison with the finger 60 by means of the lever 76, 100 loosely fulcrumed on the stud 77, rod 78, lever 79, and shaft 80. Thus when the loom is in operation the finger 60 is at its forward position and the lever 76 is in contact with the stud 75, thus keeping the nose 72 clear of the indents 65. When the weft has failed 105 and a change of shuttle takes place, the finger 60 is pushed back, as already explained, and the lever 76 is raised clear of the stud 75, when the nose 72 is forced into contact with an indent 65 of the wheel 63, and thus the 110 boss 66 rotates with the latter.

The before-mentioned tappets 7, 17, 27, and 38 (see Fig. 9) are rigidly mounted on the boss 66 and rotate with same, operating the levers 3, 19, 31, and 40, with which they are 115 held in contact by the springs 81 for the purposes already described. These tappets are so arranged that all the different movements are made during one revolution of the wheel 63, the wheels 61 and 63 being made to any 120 required ratio.

By our combination in the manner shown of the plate 52 and nose 59 with the finger 60 and lever 76 the latter is only raised for a sufficient time to allow the stud 75 to pass clear 125 of same, when it then takes up its former position.

We connect the automatic motion to the card-cylinder of the dobby, as shown by Figs. 3, 11, and 12, Fig. 11 being a front view and 130 Fig. 12 a back view, as follows: A rod 83 connects the lever 41 to the lever 84, which is secured to the shaft 85 and carries the catch 86. The shaft 85 extends through the dobby,

and a finger 87 is connected to same. Thus when the lever 41, as before explained, is operated the catch 86 turns back the cylinder 88 by its catch-wheel 89 a distance equal to 5 one lag or two picks, and at the same time the finger 87 raises the ordinary pushing-catch 90 clear of the catch-wheel 91. The catch 86 is formed so that when the cylinder 88 is being turned forward in the ordinary 10 way it is in an inoperative position. By this arrangement when the weft fails and the loom is stopped the card-cylinder 88 is reversed a space equal to two picks, thus preventing a faulty place being made in the cloth.

15 From the foregoing it will be seen that when the weft fails the clutch or change mechanism is put into operation, thus raising the box-front, ejecting the spent shuttle, placing a full shuttle in the shuttle-box of the 20 slay-board, and restarting the loom, and that during the time these movements are taking place all the primary motions of the loom are at rest.

25 What we claim as our invention, and desire to secure by Letters Patent, is—

1. In a loom, the combination, with a stationary magazine for the shuttles, of a pivoted feed-arm provided with a feed-plate *k* which normally supports a shuttle under the 30 magazine, rods *r* and *q* journaled on opposite sides of the magazine, fingers *s* and *t* secured on the rod *r* and supporting the shuttles in the magazine, rods *u* and *v* secured on the rod *q*, a bottom plate *w* secured to the rods *u* 35 and *v*, a connecting-rod pivoted to the finger *s* and rod *u*, screws *x* and *y* engaging with the rods *u* and *v* and bearing against the plate *k*, and a spring *z* which retracts the said fingers and moves the bottom plate *w* under 40 the magazine when the feed-plate is moved from its normal position, substantially as set forth.

2. In a loom, the combination, with the

shuttle-box, of the swell formed of two overlapping parts 11 and 12 having their opposite 45 ends pivoted to the back of the shuttle-box, a pin 15 carried by the front part 12 of the swell and projecting through the back part 11, a spring 16 on the said pin and holding the said parts in contact, and tappet mechanism which strikes the head of the said pin 15 when a change of shuttle takes place, substantially as set forth.

3. In a loom, the combination, with the handle 34 for operating the belt-shifting mechanism, said handle being provided with a spring which normally holds it in a non-operative position, of a revoluble tappet 38, a shaft 49 and levers 40 and 41 secured on it, a roller 39 carried by lever 40 and operated by the said 60 tappet, a pivoted lever 45 provided with a stud 46 for pushing back the handle to its operative position, and a connecting-rod 44 pivoted to the levers 45 and 41, substantially as set forth.

4. In a loom, the combination, with the pivoted weft-fork lever 51, and the weft-fork 50 carried by it; of studs 57 and 58 projecting from the said lever 51; a plate 52 having a stud 53, slots which slide over the studs 57 70 and 58, and a projecting nose 59; a spring 54 for moving the plate 52 longitudinally in one direction, change-motion mechanism, a finger 60 connected with the change-motion mechanism and arranged in the path of the 75 said nose 59, and a handle 34 for operating the belt-shifting mechanism arranged in operative connection with the said lever 51, substantially as set forth.

In testimony whereof we hereunto affix our 80 signatures in the presence of two witnesses.

ALFRED SMITH.
SIMEON JACKSON.
